(57) CLAIM

The ornamental design for an hair color dispenser, as shown and described.

DESCRIPTION

FIG. 1 is a front view of a hair color dispenser according to a first embodiment;

FIG. 2 is a rear view of the hair color dispenser shown in FIG. 1;

FIG. 3 is a right side view of the hair color dispenser shown in FIG. 1;

FIG. 4 is a left side view of the hair color dispenser shown in FIG. 1;

FIG. 5 is a top view of the hair color dispenser shown in FIG. 1;

FIG. 6 is a bottom view of the hair color dispenser shown in FIG. 1; and,

FIG. 7 is a perspective view of the hair color dispenser shown in FIG. 1.

The broken lines are for the purpose of illustrating portions of the hair color dispenser and form no part of the claimed design.
